CLAIM

The ornamental design for a goggle strap, as shown and described.

DESCRIPTION

FIG. 1 is a perspective view of a goggle strap showing my new design, it being understood that the broken line showing of a person wearing the goggle strap is for illustrative purposes only.

FIG. 2 is a rear elevational view thereof.

FIG. 3 is a top plan view thereof.

FIG. 4 is a front elevational view thereof.

FIG. 5 is a bottom plan view thereof.

FIG. 6 is a left side elevational view thereof.

FIG. 7 is a right side elevational view thereof.

FIG. 1

FIG. 2

FIG. 3

FIG. 4

FIG. 5

FIG. 6

FIG. 7
